ADJUSTING DEVICES FOR ADJUSTABLE MEMBERS SUCH AS ROLLERS

Tom Rowlands and Frank Egremont Dobson, Deptford, London, England, assignors to Molins Machine Company Limited, London, England, a British company

Application March 6, 1953, Serial No. 340,849

Claims priority, application Great Britain March 18, 1952

5 Claims. (Cl. 308—60)

This invention concerns improvements in or relating to adjusting devices for adjustable members such as rollers, such for example as corrugating rollers in machines for making corrugated board.

In such machines a web of paper is passed between a pair of opposed corrugating rollers which co-operate to form corrugations in the web. The corrugating rollers are grooved lengthwise to form teeth suitably shaped to impart corrugations of the desired shape to the web when the latter is pressed between the two rollers. The rollers must be adjustable to vary the clearance between their respective teeth, and usually one roller is on a fixed axis while the other is movable for the purpose of adjustment, and also as a safety measure in case an undue thickness of material, or a foreign body, should pass between the two rollers.

Usually the rollers are so set that the minimum clearance between the teeth is somewhat less than the thickness of the web of material being used, and the adjustable roller is resiliently pressed towards the other to squeeze the web of material between the opposed teeth of the rollers.

The rollers are normally set so as to produce the maximum squeeze and the maximum depth of corrugation in the paper board. In some cases, however, it is desirable to be able to reduce the pressure on the board and even to reduce the depth of corrugation. For example, some paper of inferior quality cannot be corrugated beyond a certain depth without cracking or breaking, and when such board is used it is necessary to limit the depth of the corrugations to the maximum which can be satisfactorily imparted to the particular paper being used. This can be done by altering the setting of the rollers so as to increase the clearance between their respective teeth.

Although, as mentioned above, one of the corrugating rollers is adjustable towards and away from the other to vary the clearance when papers of different thickness are used, usually the arrangements for making these adjustments require that the machine should be stopped and the adjustable roller re-set to obtain the correct clearance for a particular thickness of paper about to be used. In the case of paper which, due for example to its inferior quality, is to be corrugated only to a limited depth, the conditions which determine the required setting of the rollers may vary from time to time during running, even though the material being used is all of the same thickness, and generally speaking the only satisfactory way of determining the correct setting at any given time is to observe the quality of the corrugated board being produced and to adjust the adjustable roller to give the smallest clearance which will produce satisfactory corrugations in the paper which at that time is being fed through the rollers. It will be realised that if frequent changes are required, due for example to frequent variations in the quality of the paper being fed to the machine, a great deal of time would be wasted in repeatedly stopping the machine to make trial adjustments.

2

It is therefore desirable that the setting of the corrugating rollers should be adjustable while the machine continues to operate.

According to the present invention there is provided 5 a device for adjustably determining the position of an adjustable roller relatively to that of an opposed roller, comprising a member connected with the mounting for the adjustable roller and yieldable endwise to allow the latter to be pressed away from the said opposed roller, 10 and resilient pressure means (e. g. a compression spring) opposing such yielding movement, wherein the said member comprises a screw engaging with a threaded part which holds the said member against endwise movement towards the said opposed roller, and wherein there is 15 provided means to cause relative rotary movement between the said screw and the said threaded part, whereby the said member can be moved endwise to adjust the position of the adjustable roller.

The said threaded part may comprise a nut carrying 20 a wormwheel which is engageable with a worm, the said nut being urged in a direction lengthwise of the said member by the said resilient pressure means against a fixed stop, and capable of moving away from said stop against the said resilient pressure if the adjustable roller is pressed away from the said opposing roller.

Where, as in corrugating machines, the rollers employed are very large, it is convenient to mount the bearings for the adjustable roller on pivoted arms so that the roller is adjusted towards or away from the 25 opposed roller by swinging about the pivots. In that case it will be seen that the aforesaid member secured to the roller will not move in a straight line. In order to allow for this, the said member may be pivotally connected to the bearings of the adjusting roller or to a part 30 of the mounting therefor to permit rocking of the member when it is moved lengthwise by the nut, and the nut may comprise a convex surface engaging a corresponding concave seating formed on the said fixed stop, so arranged as to permit the nut to rock about the centre of the wormwheel, whereby the latter can remain in operative engagement with the worm in different angular positions of the said member. To facilitate such engagement the teeth of the wormwheel may be curved to an arc about the centre of the wormwheel.

45 The adjustable roller may be provided with a pair of adjusting devices according to the invention, one at each end of the roller, and the two devices may be capable of being operated either independently or in concert. For this purpose the worms included in the two devices 50 may be mounted on a common shaft, one of the worms being rotatable relatively to the shaft for rotation independently of the other worm, and capable of being locked on the shaft so as to be rotated by the shaft in concert with the other worm.

55 Apparatus according to the invention will now be described by way of example with reference to the accompanying drawings in which:

Figure 1 is a perspective view of a corrugating machine embodying the invention;

Figure 2 is a sectional elevation of a part of Figure 1 in the region of the arrow A.

Referring to the drawings two corrugating rollers 1 and 2 are mounted for co-operation, the roller 1 being on a fixed axis 3 while the axis 4 of the roller 2 is movable both for the purpose of adjustment and to allow the roller 2 to be pressed away from the other in the event that an undue thickness of material, or a foreign body, should pass between the rollers. The movable roller is referred to herein as "the adjustable roller."

The adjustable roller has journals 5 at its ends which run in bushes or the like 6 at the ends of a pair of arms 7 pivoted at 8, so that the roller 2 can be moved towards

and away from the roller 1 by swinging movement of the arms. The two arms may both be swung by the same amount, or one arm may be moved relatively to the other so as to position one end of the adjustable roller nearer than the other end to the opposed roller.

The position of the adjustable roller is determined by a pair of adjusting devices, shown in Figure 2, one at each end of the roller.

Each said device comprises a rod 9 pivotally secured at 10 to a part of the roller mounting, the rod being pivoted so as to allow it to rock when it is moved lengthwise. Beyond the end of the rod remote from the adjustable roller is a very strong compression spring 11 located in a fixed housing 12 and arranged to urge the rod lengthwise in a direction such as to tend to cause the adjustable roller 2 to move towards the opposed roller 1. The end of the rod against which the spring presses is rounded at 13 and engages a suitably rounded recess in a part 14 to which the spring is fixed, so as to allow for rocking of the rod. The spring is capable of being compressed somewhat if the adjustable roller (and hence the rod) is forced outwards by any undue thickness of material, or a foreign body, which may pass between the rollers.

Between the spring and the roller the rod is provided with a square thread 15 to form a screw, which passes through a nut 16. The latter is arranged to bear against a fixed stop 17 formed on a fixed part of the machine, the nut being located between the spring and the stop so that the endwise pressure of the spring on the rod causes the nut to be pressed firmly against the stop. Thus the nut holds the rod and the adjustable roller against endwise movement towards the opposed roller, while the strong compression spring, although it allows the rod to yield in the reverse direction, opposes such yielding movement and normally holds the rod firmly in the endwise position which is determined by the nut.

To enable the nut to be rotated so as to move the rod lengthwise, a wormwheel 18 is formed upon it and is arranged to engage a worm 19 which is rotatable in a manner which will shortly be described. As mentioned above, the rod, due to the swinging movement of the roller, rocks when it moves lengthwise. To allow for this rocking movement the surface of the nut which engages the stop 17 is made convex and engages a corresponding concave seating in the stop, the co-operating surfaces being curved to an arc about the centre of the wormwheel, and the parts are so arranged that the rocking of the rod causes the nut to rotate about that centre. In addition, the teeth of the wormwheel are each curved in an arc about the centre of the wormwheel. By means of this arrangement the wormwheel teeth can remain in operative engagement with the worm for different angular positions of the rod.

A device as just described is provided at each end of the rotatable roller, and the arrangements for rotating the two worms will now be described.

The two worms are carried on a cross-shaft 20 extending across the machine, and at one end of the shaft the worm for one of the adjusting devices is keyed to the shaft. At the other end the second worm is arranged to be freely rotatable on the shaft, and this worm is integral with a sleeve 21 on which is formed a handwheel 22. Thus if this handwheel is turned, one worm is rotated and thus one adjusting device is operated independently of the other.

Beyond the worm and handwheel just mentioned, a further handwheel 23 is splined to the shaft 20, and movable lengthwise along it. This further handwheel has a number of dogs 24 formed on its hub which are engageable with corresponding cross grooves 25 on the hub of the other handwheel 22, and if the splined handwheel is slid along the shaft to cause the dogs to enter the cross grooves the two handwheels can be rotated as one—that is, angular movement of either hand wheel causes rotation of the shaft and of both of the worms in concert. If the two handwheels are disengaged from each other, each can be used

to rotate one worm independently of the other. Conveniently the two handwheels are located at that end of the shaft which is the more accessible to an operator.

It will be seen that the two devices act jointly to determine the position of the adjustable roller relatively to that of the opposed roller, and by suitable use of the two handwheels the roller may be moved bodily or one end can be moved relatively to the other. In operation, the roller is first adjusted to a suitable position having regard to the paper which is to be corrugated. For good quality paper this may depend entirely on the thickness of the board, the rollers being set with a suitable clearance so as to allow the maximum depth of corrugation and in addition to squeeze the paper, the movement of the adjustable roller towards the opposed roller being limited by the engagement of the nuts against the fixed stop. Alternatively, if it is not desired to press or squeeze the paper, the clearance may be the exact thickness of the paper; or in the case of poor quality paper which cannot be corrugated to maximum depth without damage, the clearance may be greater than the thickness of the paper.

Particularly in the last-mentioned case, it is desirable that the operator should be able to watch the results of the corrugating operation as it proceeds and make what adjustments may be necessary while the machine continues to run. It will be seen that this can easily be done by suitable manipulation of one or both of the handwheels, the adjustable roller being moved towards or away from the opposed roller so as to increase or decrease the depth of corrugation according to the results being obtained.

It sometimes happens that a web of paper is slacker at one side than at the other and this may necessitate use of one of the handwheels independently of the other so as to increase or decrease the depth of corrugation at one side of the web.

If a foreign body or an excessive thickness of material (such as a double thickness of paper caused by overlapping and gumming the ends of two webs) passes between the rollers, the adjustable roller can be pressed away from the opposed roller, the compression springs compressing to allow the yielding movement. In that case each of the nuts, with the wormwheels formed thereon, will be thrust back from their fixed stops, and the wormwheel in each device may then be moved relatively to its worm, but returns into full operative engagement as soon as the roller returns by spring pressure to its proper position.

The compression spring is also adjustable by a device 26 at any time during running of the machine to vary the force it exerts on the rod. This adjustment is provided for by a threaded cap which fits over a sleeve surrounding the spring to form part of the spring housing, the cap being capable of being screwed up or down the sleeve to vary the compression of the spring.

What we claim as our invention and desire to secure by Letters Patent is:

1. Apparatus comprising an adjustable roller, a roller opposed thereto, a mounting for said adjustable roller, a member connected to said mounting and movable endwise to move the adjustable roller toward and away from said opposed roller, said member comprising a first threaded part and a cooperating threaded part having threaded engagement with said first threaded part, a fixed abutment engageable with said cooperating threaded part to limit endwise movement of said member in a direction such as to move said adjustable roller toward said opposed roller, resilient pressure means urging said member in said direction and thereby urging said cooperating threaded part against said abutment, said pressure means being capable of yielding so as to allow the adjustable roller to be pressed away from said opposed roller by excessive pressure on said adjustable roller, and whereby relative rotation of said threaded parts effects endwise movement of said member to move said adjustable roller toward or away from said opposed roller.

2. Apparatus comprising an adjustable roller, a roller opposed thereto, a mounting for said adjustable roller, a member connected to said mounting and movable endwise to move the adjustable roller toward and away from said opposed roller, said member comprising a screw; a nut threaded on said screw, gear teeth on said nut, a shaft having gear teeth thereon in engagement with said first named gear teeth, said shaft being rotatable to rotate said nut on said screw to cause endwise movement of said member; a fixed abutment engageable with said nut to prevent movement of the latter with said member in a direction such as to move the adjustable roller toward the said opposed roller, but permitting movement of said nut with said member in the reverse direction; and resilient pressure means urging the said nut in the first said direction against said abutment, said pressure means being capable of yielding to allow the said adjustable roller to be moved away from said opposed roller by excessive pressure, the said gear teeth on said nut being capable of moving with said member relatively to the gear teeth on said shaft when said adjustable roller is so moved by excessive pressure, and of subsequently returning to driving engagement when the said nut returns into engagement with said abutment.

3. A device as claimed in claim 2 including pivoted arms wherein the adjustable roller is mounted so that the roller is adjusted towards or away from the opposed roller by swinging about the pivots and the said member is pivot-

ally connected to the mounting for the adjusting roller to permit rocking of the member when it is moved lengthwise by the nut, and wherein the nut comprises a convex surface engaging a corresponding concave seating formed on the said fixed stop, so arranged as to permit the nut to rock about the centre of the wormwheel, whereby the latter can remain in operative engagement with the worm in different angular positions of the said member.

4. A device as claimed in claim 3 wherein the teeth of the wormwheel are curved to an arc about the centre of the wormwheel.

5. A device as claimed in claim 4, wherein the adjustable roller is provided with a pair of adjusting devices, one at each end of the roller, and the two devices are capable of being operated either independently or in concert, the worms of the two devices being mounted on a common shaft and one of the worms being rotatable relatively to the shaft for rotation independently of the other worm, and capable of being locked on the shaft so as to be rotated by the shaft in concert with the other worm.
